SHORT WAVE SIGNALING APPARATUS

James O. Watkins, San Francisco, Calif., assignor
to International Communications Laboratories,
Inc., New York, N. Y., a Corporation of New
York

Application September 16, 1930
Serial No. 482,190

10 Claims. (Cl. 250—20.)

This invention relates to improvements in signaling means; and more particularly to means for communication by radio upon so-called short waves or oscillations of high frequency.

5 An object of the invention is to provide a device adapted for either transmitting or receiving means utilizing short waves, to afford protection against the troublesome effects of external electrostatic capacity; thus maintaining the equipment in the desired operating condition.

A further object of the invention is to provide a simple, inexpensive, and novel appliance for obviating the influence of the body of the operator upon the apparatus in the circuits for signaling means of this type. In signaling on short waves, this "body-capacity" effect is a very serious adverse factor and, if not counteracted, will alter to a considerable extent the wave length for which adjustment has been made.

20 Heretofore metallic shields have been interposed between the operator and said circuits in an effort to screen the latter; but have usually proved to be either too complicated or insufficient.

In the practice of my invention with such a transmitter or receiver, the derangement of function that might be caused by the presence of a human body is prevented by controlling the electric potential of the carrier wave adjacent said apparatus. This result is obtained through a connection to ground by way of a suitable electric conductor of a length bearing a definite relation to the length of the carrier wave. This conductor will be fixed to a point near the apparatus, and its length will be such that a node of potential exists at said point. The outside potential of the apparatus within a considerable radius about said point is thus rendered substantially zero, and the operator's body in proximity to the circuits can no longer unbalance the apparatus or any of its parts. My invention may be thus employed when the apparatus is screened by a metal shield, which will ordinarily be included; and to the proper place on this shield the conductor will be attached.

45 Hence the high frequency potential of the shield with reference to ground, at least in the vicinity of the end of said conductor, is virtually nil; and the operator may approach as he likes without disturbing the apparatus in the smallest degree.

The nature and advantages of the invention will more fully appear from the following description, taken with the drawing; that illustrates a preferred construction in which the invention is embodied. This disclosure, however, is illustra-

tive only, and I may vary details of shape, size, arrangement of parts, or mode of proceeding to the full extent indicated by the broad and general meanings of the terms in which the appended claims are expressed.

On the drawing:

Figure 1 is a diagrammatic view showing an apparatus for signaling by radio according to my invention.

Figures 2, 3 and 4 present modifications thereof.

The same characters of reference identify the same parts throughout.

In the particular description of what the drawing presents, the numeral 1 is employed to indicate an antenna and the numeral 2 and assemblage of electrical parts operatively associated with the antenna 1. This assemblage may be of any well known design to work on relatively short waves in sending signals or receiving them. If the apparatus indicated generally at 2 is adapted for reception, oscillations will of course be transferred from the antenna 1 thereto; while if it is intended for transmission, the oscillations will be originated in the apparatus 2 and transferred to the antenna 1. For purposes of this disclosure the apparatus 2 may be regarded as a receiver, but the invention will operate with equal advantage in connection with a transmitter. In either event, the apparatus will be screened by a metal member or shield 3 in front, so that it will be between the apparatus and the operator, who adjusts the parts 2. At one point the member or shield 3 will be united to a conductor 4, the opposite end of which is connected to ground as shown at 5.

When the apparatus 2 is in operation at high frequency and oscillations are being received by the antenna 1 at high frequency, the presence of the body of the operator will interfere with the frequency adjustments to a marked extent. I have found that this disturbing influence can be counteracted entirely by means of the grounded conductor 4, provided this conductor has a length bearing a definite relation to the length of the carrier wave. For instance, substantially one-half a wave length answers my purpose, because under such conditions the point where the conductor 4 is joined to the member 3 will be at zero potential with reference to ground; and so will the earthed or grounded point 5. The middle of this conductor, however, will be at maximum potential; and for that reason the body of the conductor between the shield 3 and ground 5 should be so disposed that it cannot be ap-

proached by the operator when he is in proximity to the shield 3. This end may be attained, for example, by bending the conductor as indicated in Fig. 1, and arranging it so that it extends beneath the apparatus 2 and towards the back thereof away from the shield 3; or by otherwise placing the body of the conductor 4 so that it will be out of the way. If desired this conductor may have a length which is greater than half a wave length, such as a length equal to one, or one and one-half times the length of the carrier wave, or in fact any odd or even multiple of one-half a wave length, so long as it is connected and arranged as described above.

In series with the antenna 1 will be the usual adjustable condenser 6, which is also in series with the inductance coil 7; the latter having one terminal joined to the grid 8 of a thermionic tube, with the other terminal joined to the cathode 9 of this tube. Bridged across the leads connecting the two terminals of the coil 7 to the grid 8 and the cathode 9 is an adjustable condenser 10. The plate of the tube is shown at 11 and this plate is connected by means of a suitable conductor to one end of a regenerator coil 12, inductively associated with coil 7. The opposite end of the coil 12 is connected to one pole of an adjustable condenser 13, having its opposite terminal attached to the lead between the coil 7 and the filament 9.

The plate 11 is also in series with a radio frequency choke coil 14, which is connected to one end of the primary of an audio frequency transformer 15. One terminal of the secondary of this transformer is shown as connected to the grid 8' of a second thermionic tube having a heated cathode 9' and plate 11'. At 16 is the battery for heating the cathode 9 and suitable conductors connect the cathode 9' in parallel with the cathode 9. I also provide a battery 17 for the plates 11 and 11', this battery being joined to one terminal of the battery 16 and having its opposite pole connected by means of a conductor 19 to the plate 11'. In the line of the conductor 19 is a telephone 20. Of course the number of tubes, as regards the principle of this invention, is immaterial. As shown in Fig. 1, the antenna may be grounded by having one end of the coil 7 connected through a conductor 21 to the upper end of the conductor 4. If "body capacity" effect is to be eliminated from the batteries 16 and 17 also, these batteries are grounded by a similar conductor 4A attached to the common terminals of these two batteries. Radio frequency choke coils 18 are included in the conductors leading from the battery 16 to the cathode 9 and in the adjacent part of the conductor 19, to isolate the two grounded conductors 4 and 4A from each other, if they are not already electrically separated. The batteries need not necessarily be behind the shield 3. The terminal of the primary of the transformer 15 remote from the coil 14 may be united to the conductor 19; and the terminal of the secondary not joined to the grid 8' may be united to one of the leads between the filaments 9 and 9'.

In practice, the effect of conductor 4 is to establish a potential node on the plate 3 in the vicinity of the point to which the conductor 4 is attached. The point of attachment of the conductor 4 shown at 22 is preferably at the side or end of the panel adjacent the adjustable parts of the circuits comprising the condensers 6, 10, 13, this being the place where the radio frequency oscillations mostly occur. With the conductor 4

so connected, the operator may approach the panel 3 at any time and the body capacity, due to the presence of the operator, will have no disturbing effect. He may even touch the panel 3 near the point 22 with his fingers. It is important, however, that the greater portions of the conductors 4 and 4A between the attached and grounded ends be removed as much as possible as indicated in Fig. 1 by bending these conductors beneath the shield 3 and in a rearward direction. The mid-point of wires 4 and 4A, assuming these to be half a wave in length, has a maximum potential because a potential loop exists thereat; and disturbances would follow if the body of either wire between the two ends thereof were located at some point where it would be close to the operator when the latter adjusts any part of the apparatus 2.

Figure 2 shows a modification wherein the antenna 1 has a separate ground 23 and is not united to the point 22.

Figure 3 shows a grounded wire such as 4' containing an adjustable inductance 24, the total effective length of this wire also being any odd or even multiple of one-half a wave length.

Similarly, Figure 4 shows grounded conductor 4' with an adjustable condenser 25 in the line thereof, and the effective electrical length of this conductor is likewise any odd or even multiple of one-half a wave length.

With the inductance and capacity present, the actual length of the conductors 4' can be shortened if there is a scarcity of available space; and by making these elements adjustable, the desired effects can be obtained with different wave lengths for the receiver or transmitter.

As described above in connection with Fig. 1, the body of the conductor 4' in either Figures 3 or 4 must be so disposed that it cannot be approached by the operator and is preferably put beneath the panel 3 and to the rear thereof.

Radio frequency choke coils may also be utilized in the connections for the telephone 20. The arrangement of circuits shown is intended to be for example only, and may be varied with wide limits.

The part of the shield 3 where the conductor 4 is joined is at substantially ground potential; which is virtually zero. Hence external capacity adjacent this part of the shield does not affect the apparatus 2 at all. Some potential may exist at the opposite end of the shield, but this creates no difficulty because even there the potential can be kept at a low value and the operator in making adjustments will stand close to the end where the wire 4 is attached.

With this device, the disturbing effect of external capacity, due to the presence of the operator, or in fact external capacity of any kind, is entirely counteracted; and this scheme works just as well on a transmitting circuit as upon a receiving circuit. To gain my end it is only necessary to connect a grounded conductor as set forth, and by this simple and inexpensive dimension the stable operation is assured.

Having described my invention, what I believe to be new and desire to secure and protect by Letters Patent of the United States is:

1. A device for preventing external electrostatic capacity from disturbing radio signaling means including an antenna and apparatus between which and the antenna electrical oscillations are transferred, a shield for said apparatus, said antenna and said apparatus comprising adjustable elements for radio frequency oscillations

adjacent one end of said shield, and a conductor connected to said end of said shield and being grounded, the conductor having a length equal to a multiple of a half wave length of said oscillations and having the greater portion of its length disposed as far as possible from said apparatus.

2. A device for preventing external electrostatic capacity from disturbing radio signaling means including an antenna and apparatus between which and the antenna oscillations of high frequency are transferred, said apparatus comprising a thermionic tube having a cathode and an anode, means for supplying said cathode and anode with electrical energy, and means for connecting said supplying means to ground, said connecting means comprising a conductor having a length equal to a multiple of a half wave length of said oscillations, with the body of the said conductor arranged to be remote from said apparatus.

3. A device for preventing external electrostatic capacity from disturbing radio signaling means including an antenna and apparatus between which and the antenna electrical oscillations of high frequency are transferred, said apparatus containing adjustable elements for radio frequency oscillations, a shield for said apparatus, means comprising a conductor connected to said shield and to ground and having a length equal to a multiple of a half wave length of said oscillations, the body of said conductor being comparatively remote from said apparatus and said shield, said apparatus comprising a thermionic tube containing cathode and anode, means for supplying electric energy to said cathode and anode, choke coils between said supply means and said tube, and means for grounding the supply means by a conductor having an effective length equal to a multiple of a half wave length of said oscillations.

4. A device for preventing external electrostatic capacity from disturbing radio signaling means including an antenna and apparatus between which and the antenna oscillations of high frequency are transferred, said apparatus having thermionic tubes, means for supplying electrical energy to said tubes, and a shield before said apparatus, said device consisting of conductors connected to ground at one end and separately to said supply means and said shield at their opposite ends and having an effective

length equal to a multiple of a half wave length of said oscillations.

5. A device for preventing external electrostatic capacity from disturbing radio signaling means including an antenna and apparatus between which and the antenna electrical oscillations of high frequency are transferred, said device comprising a shield in front of said apparatus and a conductor connected to ground at one end and to the shield at the other, and of a length to impose on the shield in the vicinity of its point of connection therewith a potential node at the frequency of said oscillations.

6. A device for preventing external electrostatic capacity from disturbing radio signaling means including an antenna and apparatus between which and the antenna electrical oscillations of high frequency are transferred, said apparatus comprising a thermionic tube, means for supplying electrical energy thereto, and a grounded conductor connected to said means, said conductor having a length bearing a definite relation to the wave length of said oscillations, and bearing a potential node at its point of connection with said means.

7. The device according to claim 6, wherein radio frequency choke coils are interposed between said apparatus and said means.

8. The method of avoiding body capacity effects in a radio signaling device including a shield and a ground connection therefor which consists in adjusting the inductance of the ground connection according to the signal frequency to produce a voltage node at the shield, thereby rendering said signaling device substantially non-responsive to the effects of body capacity.

9. A device for preventing external electrostatic capacity from disturbing radio signaling apparatus, comprising a shield for the apparatus, and a ground connection therefor of such length as would produce a voltage node on the shield at the frequency of the signaling wave.

10. In a radio signaling device, an antenna member, tuning means therefor, a detector device associated therewith, control means for said tuning means, a shield between said tuning means and said control device, and a ground connection for said shield having a length and inductance such as to produce a voltage node on said shield at the frequency of the signaling wave.
